UNITED STATES PATENT OFFICE

103,519

DESIGN FOR A SHADE BRACKET OR SIMILAR ARTICLE

Benjamin E. Sense, Mahoningtown, and James L. Cole, New Castle, Pa.

Application December 24, 1936, Serial No. 66,744

Term of patent 14 years

To all whom it may concern:

Be it known that we, Benjamin E. Sense and James L. Cole, citizens of the United States, residing, respectively, at Mahoningtown and New Castle, in the county of Lawrence and State of Pennsylvania, have invented a new, original, and ornamental Design for a Shade Bracket or Similar Article, of which the following is a specification, reference being had to the accompanying drawing, forming part thereof.

Figure 1 is a view in side elevation of a shade bracket embodying our design;

Figure 2 is a front elevation of the same.

We claim:—

The ornamental design for a shade bracket or similar article, as shown.

BENJAMIN E. SENSE.
JAMES L. COLE.
